UNITED STATES PATENT OFFICE

2,417,479

NEEDLE LATCH GUARD

Oscar Fregeolle, Central Falls, R. I., assignor to
Hemphill Company, Central Falls, R. I., a corporation of Massachusetts

Application December 21, 1945, Serial No. 636,441

3 Claims. (Cl. 66—14)

1

This invention relates to a new and useful improvement in knitting machines of the circular, independent needle, type having superposed axially aligned needle cylinders. Its object is to provide means for controlling the latches of certain needles at a certain critical time.

As is well known, a machine of this type is well adapted for production of true rib fabric widely used in hosiery and still more widely in the tops of stockings having plain legs and feet. The machine is provided with double ended needles capable of knitting in either the upper or lower cylinder. When knitting in the lower cylinder they produce typical plain fabric and if associated with needles knitting in the upper cylinder they produce true rib fabric, the outstanding and depressed wales of which are knit by needles operating in the lower and upper cylinder, respectively. All of the needles are operated by sliders positioned in the corresponding cylinder slots so as to be engageable with the idle hooks of the needles.

Assuming that some of the needles have been operating in the upper cylinder in the production of a true rib stocking top, for example, and that the leg is to be of plain fabric, it is necessary that the needles which have been working in the upper cylinder be transferred to the lower cylinder before plain knitting begins. To transfer these needles to the lower cylinder, it is necessary to uncouple them from the upper cylinder sliders and to couple them to the corresponding sliders of the lower cylinder. To uncouple the sliders they are swung out radially of the cylinder slots by a suitable mechanism called a needle divider until their hooks are clear of the needle hooks to which they have been connected.

As is well known, the latches of the needles should be controlled by some positive means to keep them from opening or closing as the case may be except at such times as their free action is required. For this purpose, the machine may be provided with a latch ring or guard sufficiently close to the cylinder so that the needle latches will be retained substantially in their open or closed position as the case may be. However, during transfer the necessary outward movement of the upper cylinder sliders to uncouple them from their needles causes them to project considerably beyond the cylinder adjacent the point of transfer. Therefore, the latch guard has to be omitted or withdrawn at this point with the result that the latches of the lower cylinder needles in this area may be left without control

2

and may open or close and in so doing may be damaged or rendered unsuitable for the subsequent knitting operation.

This difficulty has been minimized in some two cylinder machines such, for example, as that disclosed in the application for U. S. Letters Patent #559,136, filed October 18, 1944, by closing the gap in the latch guard in the area of transfer by means of a resilient or outwardly movable element which will swing out with the sliders when they are uncoupled from their needles and yet maintain an approximation of the true circle which the latch guard should be. This is not wholly satisfactory in all cases because the outward swing of the sliders may be so great that this section of the latch guard may be withdrawn so far that some of the needle latches will miss it entirely or strike it when they are in a horizontal position so that it is not always effective to keep the latches open or closed as desired or to prevent damage to them. The primary object of this invention is to provide simple and positive means of keeping open the latches of lower cylinder needles while needles which have been working in the upper cylinder are being transferred to the lower cylinder. The needles being transferred require no special control with respect to their upper latches because the usual upper slider is long enough to cover the latch so that it is prevented from closing.

The machine selected for illustration herein without any intention of limiting the invention thereto, is substantially that of the patent application referred to above. It is also shown in the drawing of which:

35 Fig. 1 is a plan view of a cylinder surrounded by a latch guard having a resilient element spanning the gap in the area of needle transfer;

Fig. 2 is a detail of the same cylinder and latch ring showing how the resilient element is distorted outwardly by the outward swing of the sliders when they are uncoupled from their needles, the sliders being shown partly in section;

45 Fig. 3 is a detailed view of a needle showing an upper cylinder slider uncoupled from the needle during its transfer to the lower cylinder; and

Fig. 4 is a similar view of an adjacent lower cylinder needle showing means whereby its latch is kept open during transfer of other needles from the upper to the lower cylinder as shown in Fig. 3.

The latch ring or latch guard referred to is 55 shown at 1 in Fig. 1 surrounding the upper cylin-

der 2. The gap in latch ring 1 is shown at 3. This is spanned by a resilient element shown as four springs 4 in Figs. 3 and 4, the upper one of which is also shown in Figs. 1 and 2. These springs substantially complete the circle around the needle circle otherwise formed by ring 1. A needle 5, assumed to have been operating in upper cylinder 2 by means of its slider 6, is shown in Fig. 3. An adjacent needle 7 assumed to have been operating in the lower cylinder 8 and a corresponding upper cylinder slider 9 is shown in Fig. 4. A slider 9 should be provided in the upper cylinder for each of the needles 7 operating in the lower cylinder which are in the transfer area represented by gap 3 while any upper cylinder needle 5 is being transferred to the lower cylinder.

When such transfer occurs upper cylinder slider 6, still connected to its needle 5, is moved down until its end 10 engages a suitable device, such as needle divider 11, whereby it is swung out radially of upper cylinder 2 until it is disengaged from the needle as shown in Fig. 3. When this occurs springs 4 which normally extend straight across gap 3 as shown in Fig. 1 are swung out by the divider as shown in Figs. 2, 3 and 4. The latch of adjacent needle 7 assumed to be operating in lower cylinder 8 which should be open at this time would, were it not for slider 9, be unprotected with the result that the latch might swing up and strike the withdrawn springs 4 in such a way as to be damaged or they might even pass completely by springs 4 and close.

Slider 9 may be identical to slider 6 and may be operated by the same cam with the exception that its shank should be shorter than that of slider 6 so that when slider 6 has reached its lowermost position during transfer as shown in Fig. 3, the tip 12 of slider 9 will cover latch 13 of needle 7 and will not descend far enough so that its hook 14 will connect with hook 15 of needle 7 as shown in Fig. 4. Slider 9 and its operating device may be of any construction other than that just suggested so long as it meets the above operating requirements.

In this way, the latches of the lower cylinder needles are positively controlled during transfer of needles from the upper to the lower cylinder whenever springs 4 cannot serve effectively for this purpose. As a matter of fact, as far as this invention is concerned, springs 4 or their equivalent may be omitted since the latches of the transferred needles are controlled by sliders 6 and the latches of the lower cylinder needles by sliders 9. The number of sliders 9 which should be used will vary with the character of the machine and the judgment of the operator. It is sufficient that a slider 9 be provided for each lower cylinder needle requiring latch control while it is passing through the transfer area, represented by gap 3, while transfer is taking place. If the true rib work has been the well known 6 x 3 or 1 x 1 true rib followed by plain fabric, a

full complement of sliders 6 and 9 would, presumably, be used. For other work, fewer sliders 9 might be sufficient. The necessary number and arrangement of both kinds of sliders will depend upon the nature of the work being done. Although, as already stated, springs 4 may be omitted without affecting the operation of this invention, something of this sort is usually necessary to control the latches of the instep group of needles during the knitting of the heel and toe by the short butt needles.

I claim:

1. In a circular knitting machine of the superposed, coaxial cylinder type provided with needles adapted to knit in either cylinder, sliders in each cylinder for operating the needles which knit therein, means for disconnecting from upper cylinder needles the corresponding upper cylinder sliders so that said needles can be transferred to the lower cylinder and means for controlling the latches of adjacent lower cylinder needles only during such transfer.

2. In a circular knitting machine of the superposed coaxial cylinder type provided with needles adapted to knit in either cylinder, sliders in each cylinder for operating the needles which knit therein, means for disconnecting from upper cylinder needles the corresponding upper cylinder sliders so that said needles can be transferred to the lower cylinder and means for controlling the latches of adjacent lower cylinder needles only during such transfer comprising a slider in the upper cylinder for each said adjacent needle adapted to overlay the latch of the corresponding lower cylinder needle during transfer.

3. In a circular knitting machine of the superposed, coaxial cylinder type provided with needles adapted to knit in either cylinder, sliders in each cylinder for operating the needles which knit therein, cams for operating the sliders, means for disconnecting from upper cylinder needles the corresponding upper cylinder sliders so that said needles can be transferred to the lower cylinder and means for controlling the latches of adjacent lower cylinder needles only during such transfer, said last mentioned means consisting of corresponding sliders positioned in the upper cylinder slots, said sliders being long enough to overlie the latches of the corresponding lower cylinder needles when adjacent upper cylinder needles are being transferred to the lower cylinder but too short to reach needle engaging level when the sliders involved in transferring are at that level.

OSCAR FREGEOLLE.
